UNITED STATES PATENT OFFICE.

WILLIAM O. PORTER, OF CHICAGO, ILLINOIS.

ATTACHMENT FOR BATHTUBS.

Application filed May 26, 1922. Serial No. 563,820.

To all whom it may concern:

Be it known that I, WILLIAM O. PORTER, a citizen of the United States, residing at Chicago, in the county of Cook and State of Illinois, have invented certain new and useful Improvements in Attachments for Bath-tubs, of which the following is a specification.

My invention relates to a supporting device to be mounted upon a bath tub, and serving to hold a clothes wringer.

An important object of the invention is to provide a device of the above mentioned character which may be conveniently placed in position upon and within a bath tub, and subsequently clamped to the bath tub and hence adapted to serve as a rigid support for a clothes wringer.

A further object of the invention is to provide a device of the above mentioned character, which is simple in construction, strong and durable.

Other objects and advantages of the invention will be apparent during the course of the following description.

In the accompanying drawings forming a part of this specification and in which like numerals are employed to designate like parts throughout the same,

Fig. 1 is a side elevation of a supporting device embodying my invention,

Fig. 2 is a plan view of the same,

Fig. 3 is a central longitudinal section,

Fig. 4 is a transverse section taken directly in front of and looking towards the feed wheel and actuating lever.

Fig. 5 is an enlarged detail section through the feed wheel and associated elements.

Fig. 6 is a detail view of the feed wheel hub supporting plate.

In the drawings, wherein for the purpose of illustration is shown a preferred embodiment of my invention, the numeral 5 and 6 designate adjustable support sections, constituting the body portion of the support.

The support section 6 embodies spaced parallel bars 7, which are rigidly secured together by transverse straps 8, 9 and 10, while any other suitable means may be employed, if desired. The strap 10 is secured to the extreme ends of the bar 7 and carry knobs 11, preferably formed of rubber. The strap 10 is bent inwardly between the ends of the bars 7, forming a U-shaped portion 12, and this U-shaped portion has its ends apertured for pivotally receiving the ends of an ap-

proximately U-shaped suspension hook 13, which is preferably resilient. The support section 5 embodies spaced bars 14, rigidly connected by transverse straps 15 and 16, as shown. The strap 15 is secured to the extreme outer ends or edges of the bars 14 and carry knobs 16', preferably formed of rubber. The strap 15 has its inner portion bent inwardly between the bars 14, in the form of a U-shaped portion 17, the ends of which are apertured for pivotally receiving the ends of a preferably resilient suspension hook 18, as shown.

Arranged between the bars 14 is an inner bar 19, rigidly secured to the transverse straps 16 and projecting inwardly beyond the bars 14 and slidably mounted between the bars 7. The inner bar 19 has a pair of transverse guide plates 20 rigidly secured to its inner end, upon opposite sides thereof. These guide plates slidably contact with the opposite faces of the bar 7 and operate between the transverse straps 8 and 9, as shown.

The numeral 21 designates a feed screw, extending longitudinally between the bars 7 and rigidly connected with the inner end of the inner bar 19 by any suitable means. The numeral 22 designates a feed wheel, having a tubular hub 23, interiorly screw-threaded to engage upon the feed screw 21. The feed wheel is free to rotate but cannot move longitudinally perceptibly, and for this purpose it is rotatably mounted within openings 24', formed in plates 24, formed integral with the upper strap 9. The wheel 22 slidably engages one plate 24 while a flange 25 upon the opposite end of the tubular hub slidably engages the end 26 of a lever 27, this end engaging the other plate 24.

The lever 27 has a double ended pall 28 pivoted thereto, either end of which is adapted to be thrown into engagement with the teeth 29 of the wheel 22. It is thus seen that the lever may be oscillated to turn the feed wheel in opposite directions.

The numeral 30 designates an attaching bar, arranged above the bars 7 and rigidly secured thereto by straps 31 or the like. The attaching bar 30 has frame members 32 of the wringer clamped thereto, as shown in Fig. 1.

In the use of the device, the lever 27 is operated with the pall 28 shifted in the desired direction, to bring the support section 5 toward the supporting section 6, whereby

the body portion of the device is suitably contracted so that it may be readily inserted within the tub. When applied to the tub, the suspension hooks 13 and 18 engage over 5 the top edges of the tub and hence hold the device in place, prior to the clamping action. The lever and pall 28 are now properly actuated to expand the body portion, the support section 5 moving longitudinally away 10 from the support section 6, whereby the knobs 11 and 16, which are suitably yielding, have clamping engagement with the inner walls of the tub. This clamping engagement serves to rigidly lock the device to the tub, 15 against the downward weight. It is obvious that the clothes wringer may be employed in the usual manner to wring the clothes, which may be washed in the bath tub. The clothes wringer may be readily removed from the 20 attaching bar 30, as is obvious.

It is to be understood that the form of my invention herewith shown and described is to be taken as a preferred example of the same, and that various changes in the shape, 25 size, and arrangement of parts may be resorted to without departing from the spirit of my invention, or the scope of the subjoined claims.

Having thus described my invention, I 30 claim:

1. A device adapted to be applied to a tub and serving to support a clothes wringer,

comprising a body portion including a pair of support sections provided at their outer ends with yielding knobs adapted to contact with the inner walls of the tub, means to move one support section longitudinally with relation to the other support section, suspension hooks secured to the outer ends of the support sections and adapted to engage over the top edges of the tub, and an attaching bar arranged above one support section and secured thereto, said attaching bar being adapted to have the clothes wringer clamped thereon. 45

2. A device adapted to be applied to a tub and serving to support a clothes wringer, comprising a body portion embodying a plurality of sections having slidable engagement with each other whereby one section may be moved longitudinally with relation to the other section, compression elements carried by the ends of said sections to engage with the inner walls of the tub, suspension elements secured to the ends of said sections to engage over the top of the tub, a feed screw secured to the inner end of one section, a feed wheel mounted upon the feed screw and held in place upon the other section, and means to turn the feed wheel. 55 60

In testimony whereof I affix my signature.

WILLIAM O. PORTER.
